COMBUSTION HEATER WITH FUEL RETAINING TROUGH AND IGNITER POCKET

Henry J. De N. McCollum, deceased, late of Chicago, Ill., by Thelma McCollum, executrix, Chicago, Ill., assignor to Stewart-Warner Corporation, Chicago, Ill., a corporation of Virginia

Application October 3, 1945, Serial No. 619,980

4 Claims. (Cl. 158—28)

1

This invention relates to internal combustion heaters and is particularly concerned with the type in which the fuel arrives at the combustion chamber in liquid form and is there mixed with air for combustion.

One object of the invention is to provide means for insuring a proper intermixture of the air and liquid fuel without employing a spray nozzle for breaking up the fuel, or premixing means anterior to the burner.

Another object of the invention is to provide a combustion chamber into which the fuel is introduced in liquid form, the chamber itself being shaped to provide a trough to retain liquid fuel until it is vaporized by the heat of the combustion chamber and by contact with the air introduced therein.

It is also an object of the invention to provide an internal combustion heater with a combustion chamber having a portion in which combustion of the fuel is initiated, together with a pocket adjoining said portion of the combustion chamber with means for delivering liquid fuel to the pocket and ignition means in the pocket capable of at least partially vaporizing such liquid fuel and igniting the vapor for admixture with air introduced into the adjoining portion of the combustion chamber.

A further object of the invention is to provide an internal combustion heater having a combustion chamber with means for introducing combustion air into a portion of the chamber, and ignition means closely adjoining said portion of the combustion chamber but protected from the air flow in a manner which prevents cooling of the ignition means.

Other objects and advantages of the invention will appear from the following description taken in connection with the drawings, in which:

Fig. 1 is a vertical axial sectional view of an internal combustion heater which includes certain features embodying this invention;

Fig. 2 is an end elevation of the heater shown in Fig. 1, as indicated in line 2—2 on Fig. 1;

Fig. 3 is a vertical sectional view of a heater embodying a modification of the invention, a portion of the heater being broken out to condense the view;

Fig. 4 is a transverse detail section taken as indicated on line 4—4 of Fig. 3;

Fig. 5 is a transverse sectional view taken as indicated on line 5—5 of Fig. 3, and on a larger scale;

Fig. 6 is a fragmentary vertical sectional view

2

of a heater embodying another modification of the invention;

Fig. 7 is a fragmentary vertical sectional view showing another modified form of the invention;

Fig. 8 is a fragmentary sectional view similar to Fig. 7, but showing a further modification;

Fig. 9 is a detail section taken as indicated on line 9—9 of Fig. 8.

In heaters of the internal combustion type, one of the major difficulties in employing liquid fuel involves obtaining adequate intermixture of the fuel and air, and to meet this problem spray nozzles are sometimes used to atomize the fuel, or premixing burners are employed, in which the fuel and air are more or less mechanically intermingled before introduction into the combustion chamber. The present invention undertakes to dispense with the use of spray nozzles or premixers and to accomplish a satisfactory intermingling of fuel and air in the combustion chamber itself with the aid of relatively simple structural features.

In each form of the invention herein illustrated, the fuel is delivered in liquid form and at least a portion of the fuel is received in liquid form in a pocket closely adjoining the combustion chamber and communicating therewith. The igniting means is arranged in the pocket or adjacent thereto so that a portion of the fuel will be promptly vaporized by the heat of the igniter and then ignited in the pocket, which thus becomes a portion of the combustion chamber. In addition, the portion of the combustion chamber adjoining the pocket is so shaped as to serve as a trough to retain fuel which may not be immediately vaporized and to prevent it from escaping into the general combustion space until it has been properly vaporized and mixed with combustion air.

As shown in Fig. 1, the heater is of the type arranged for heating water which may serve as the heat transmitting medium or vehicle in a system having radiators through which the water is circulated. The heater includes a main combustion space 10 surrounded by a water jacket 12 and with a second water jacket 14 spaced from the jacket 12 by an intermediate annular space 16 which communicates at one end with the combustion space 10, and at the other end with an exhaust passage 18. The water inlet pipe is shown at 20 connecting with both water jackets 12 and 14, and the water outlet pipe 22 connects with both jackets at the opposite side of the heater through an elbow 24. Air for combustion is supplied by a blower 26 discharging into a conduit

28 which terminates in a right angle bend at 30, discharging tangentially into one end of the combustion space which is defined by a frusto conical shell 32. The smaller end of the shell 32 opens into the general combustion space 10 and the larger end is closed by a flat wall 34. A pocket 36 opens through the wall 34 into the initial portion of the combustion space defined by the shell 32.

Liquid fuel is supplied through a pipe 38 to a delivery opening 40 in a block or fitting 42 secured to one side of the pocket 36 and an igniter 44 of the hot wire type is supported in the pocket 36 extending downwardly near the bottom wall thereof. This type of heater is designed to be mounted with the axis of its cylindrical chamber 10 and surrounding jackets in a substantially horizontal position so that the floor or bottom wall of the pocket 36 is normally horizontal, while the lower portion of the shell 32 is inclined upwardly from the end wall 34 toward the main combustion space 10.

The liquid fuel introduced at 40 drips or flows on to the floor or bottom wall of the pocket 36, and a portion of this fuel is readily vaporized by the radiant heat of the igniter 44. The air entering the shell 32 at 30 in tangential relation to the circular outline of the shell 32, sweeps around it with a whirling motion, entraining the vapor from the pocket 36 and forming a combustible mixture therewith. This mixture is initially ignited by contact with the igniter 44, and thereafter the additional vapor entering the shell 32 from the pocket 36 is ignited by contact with the flaming gas already burning therein. The tapered form of the shell 32 tends to confine the whirling mixture initially until combustion is well established because the centrifugal action operates to drive the liquid portion of the mixture toward the larger end of the shell 32 which is adjacent its end wall 34. The liquid particles are thus retained in the shell 32 and whirled about with the air until they are vaporized and more completely intermingled with the air, thus insuring more nearly perfect combustion.

Whenever the liquid fuel enters the pocket 36 more rapidly than it can be vaporized by the heat of the igniter 44 or the heat radiated from the combustion chamber itself, the excess of liquid fuel will run into the shell 32 and will accumulate in the lower portion thereof adjacent the back wall 34, which thus provides a trough at 33 in which the liquid fuel is retained but exposed to the whirling stream of air and to the heat of burning gases in the shell 32, so that this liquid fuel is rapidly changed to vapor and thoroughly mixed with air for combustion. As already indicated, combustion of the mixed fuel and air continues and proceeds longitudinally in the shell 10, the products of combustion flowing toward the end wall 11 and then reversing their direction and flowing through the space 16 to the exhaust passage 18.

Fig. 3 illustrates a slightly different form of heater, in which the purpose is to heat a stream of ventilating air flowing in heat exchange relation with the products of combustion. The cylindrical casing 50 encloses a motor 52 which drives a fan 54 for drawing ventilating air through the casing and through the longitudinal passages 56 which are provided between the turns of a spirally formed passage 58 in which products of combustion flow from the combustion chamber 60. Air for combustion is drawn through the combustion space in a conduit 62 where it is pre-

heated. From the conduit it is delivered to the central portion of a blower wheel 64 arranged to be driven by the same motor 52 which drives the fan 54, and this wheel delivers the air centrifugally into an air chamber 66 which jackets one end of the frusto conical shell 68 forming the burner or initial portion of the combustion chamber. The air enters the shell 68 through ports 70 therein and adjacent these ports the vanes 72 direct the flowing air tangentially against the inner surface of the shell 68 so that a whirling action of the air is thus produced within the burner shell. The larger end of the frusto conical shell 68 is closed by a flat wall 74, and a pocket 76 is secured against the outer face of the wall 74 but communicates with the interior of the shell 68 through ports 78 and 80 in the wall 74.

As shown in Fig. 5, a fuel inlet pipe 82 delivers fuel to the pocket 76 through an orifice 84, and the enclosing shell 86 of the hot wire igniter 88 is mounted in the pocket close enough to the orifice 84 so that the liquid fuel will become vaporized by passing near the igniter. However, if some of the liquid is not vaporized, it will collect in the bottom of the pocket and may drain through the lower portion of the port 80 into the larger end of the shell 68. At this point a trough 90 is formed to receive the liquid fuel and retain it until it can be vaporized and swept away by the whirling currents of air and combustible mixture in the shell 68. From the shell 68 the products of combustion pass into the space 60 and thence through the spirally formed jacket 58 to the exhaust passage 92 leading therefrom. The details of this spiral heat exchanger form no part of the present invention and need not be further described in this connection.

When a frusto-conical shell is used for the initial portion or burner space of the combustion chamber as described, a substantial pressure drop is caused by the progressive constriction of the rotating air mass and by turbulence at the point where the products of combustion flow suddenly from the small diameter opening of the burner into the larger space. If less pressure drop is advisable, the arrangement shown in Fig. 6 is of advantage. The frusto-conical burner shell 94 is mounted within the outer casing 96 and is provided with a pocket 98 to which the fuel is fed through a pipe 100 and in which the igniter 102 of the hot wire type is located. The combustion air is introduced at 104 and sets up a whirling action within the shell 94 in the same manner as in the forms of the invention already described. But instead of feeding directly into the main combustion space 106 the conical shell 94 is connected by a short cylindrical portion 108 with a reversely frusto-conical or flaring section 110 so that the three sections 94, 108 and 110 approximate the form of a venturi and a large percentage of the pressure drop is recovered as the gases flow through the flaring section 110 into the space 106.

In the burner shell 172 shown in fragmentary fashion in Fig. 7, the bottom wall 174 of the pocket 176 adjoining the burner shell 172 is continuous with the wall of the shell 172, but a false bottom or pan 178 is provided in the pocket to receive the liquid fuel which drips from the feed orifice 180 to which the feed pipe 182 leads. In this structure the igniter is shown as a spark plug 184 for high tension current and having an electrode 186 which extends near the surface of

the liquid fuel in the pan 178 so that the spark will normally jump to the pan 178 which is grounded and must thus pass through the liquid fuel, serving to vaporize and ignite a portion of it. The air for combustion enters tangentially at 188, causing the same whirling action as in previously described structures and producing a combustible mixture by contact with the liquid fuel in the pan 178 and the vapor produced therefrom; and of course this combustible mixture is ignited as soon as the spark from the electrode 186 becomes effective. If the liquid should be supplied at such a rate as to overflow the pan 178, it will accumulate on the floor 174 of the pocket which forms a trough by which the excess liquid is retained for exposure to the sweep of the air and burning gases by which it is eventually absorbed as a portion of the combustible mixture.

In the arrangement shown in Fig. 8, the frusto-conical burner shell 190 has a pocket 192 attached to its end wall 194, and as shown in Fig. 9 the partition 196 which separates the pocket 192 from the interior of the shell 190 is formed with a pair of ports 198, 198 which extend from top to bottom of the pocket and through which air may enter the pocket and a combustible mixture of air and fuel vapor may leave the pocket in the same manner as in previously described structures—for example, that of Figs. 3, 4, and 5. But in this arrangement the fuel entering through the pipe 200 flows directly onto the surface of the insulating sheath 202 which encases the upper portion of the electrode 204 of the igniter plug 206 and the liquid thus follows the electrode 204 downwardly and flows off the end of the electrode to the floor 208 of the pocket 192. The spark which jumps from the end of the electrode 204 to the floor 208 is thus certain to pass through the liquid fuel itself so as to vaporize and ignite a portion of it to initiate combustion. Any accumulation of liquid fuel on the floor of the pocket 192 will flow through the ports 198 into the lowest portion of the frusto-conical shell 190 with which the floor 208 of the pocket 192 is aligned so that a trough is thus provided at 210 in which the liquid fuel is subjected to the sweep of the air and flaming products of combustion whirling around the burner chamber 190 and acting to vaporize and ignite this fuel.

While there is shown and described herein certain structure illustrating the invention, it is to be understood that the invention is not limited thereto or thereby but may assume numerous other forms and includes all modifications, variations and equivalents coming within the scope of the following claims.

Having thus described the invention, what is claimed as new and desired to be secured by Letters Patent is:

1. In a heater, means forming a combustion chamber of substantially circular cross section, air inlet means admitting air to said chamber in transverse relation to the axis of its circular form and producing a whirling action, means forming a pocket adjacent said chamber having an inlet opening and an outlet opening both providing communication between the chamber and the pocket, liquid fuel inlet means discharging into said pocket, igniting means in said pocket out of the path of the whirling gases in said chamber and positioned to heat and vaporize liquid fuel therein, said combustion chamber forming means

including a trough to receive and hold unvaporized liquid fuel in the path of the whirling gases and at least one of said pocket openings extending adjacent the bottom of the pocket in position to drain fuel therefrom into said trough.

2. In a heater, means forming a combustion chamber having a frusto-conical wall and an adjoining wall which meets said conical wall at an acute angle forming a trough, means delivering air to said chamber in transverse relation to the axis of said frusto-conical wall and producing a whirling motion of said air about said axis of said wall and over said trough, said chamber forming means including means forming a pocket adjacent said adjoining wall, igniting means in said pocket, fuel inlet means discharging liquid fuel into said pocket in proximity to said igniting means, said pocket communicating with the conical portion of the combustion chamber through an opening in said adjoining wall which extends to the bottom of the pocket to permit liquid fuel in said pocket to drain into the said trough for exposure to the whirling air stream in the chamber and to permit an interchange of combustion air and products of combustion between said pocket and said chamber.

3. In a heater, means forming a combustion chamber having a frusto-conical wall and an adjoining wall which meets said conical wall at an acute angle forming a trough, means delivering air to said chamber through an opening in one of said walls, a vane adjacent said opening directing the air stream in transverse relation to the axis of the frusto-conical wall and causing a whirling motion of said air about said axis of the frusto-conical wall and over said trough, means forming a pocket adjacent said adjoining wall in communication with the chamber to permit an interchange of combustion air and products of combustion between said chamber and said pocket, fuel inlet means supplying liquid fuel to said pocket to form with said air a combustible mixture, and igniting means in said pocket shielded from the air stream in the chamber.

4. In a heater, means forming a horizontal combustion chamber having a frusto-conical wall and transaxial adjoining wall which meets said conical wall at an acute angle at the larger end of its conical form to provide an annular trough, means delivering air to said chamber through an opening in one of said walls, a vane adjacent said opening directing the air stream in transverse relation to the axis of the frusto-conical wall and causing a whirling motion of said air about said axis of said wall and over said trough, said chamber including means forming a pocket adjacent said adjoining wall in communication with the remainder of the chamber to permit an interchange of combustion air and products of combustion between said pocket and the remainder of said chamber, fuel inlet means discharging liquid fuel to said pocket to form with said air a combustible mixture, and igniting means in said pocket shielded from the air stream in the chamber, said trough serving to collect unvaporized liquid fuel and to expose it to the air stream sweeping around the chamber.

THELMA McCOLLUM.
Executrix of the Last Will and Testament of
Henry J. De N. McCollum, Deceased.
